BOTTLE FILLING MACHINERY

George J. Valavan, Mount Vernon, N. Y.

Application December 3, 1938, Serial No. 243,761

7 Claims. (Cl. 226—111)

This invention relates to bottle filling machinery, and is particularly directed to a filling machine valve to control the filling of bottles with carbonated beverages and beer.

Heretofore in filling machinery for filling bottles with carbonated beverage or beer, the pressure in the beverage supply tank had to be sufficient to press the beverage into the bottle and compress the air in the bottle, the air in the bottle being released only when the bottle came down after being filled. In accordance with the present invention, less pressure is needed in the beverage tank because it is not required to compress the air in the bottle while filling the bottle, means being provided to release the air in the bottle as the bottle is being filled. By releasing the air from the bottle as it is being filled, the filling operation is faster than in prior machines, in which the air is not released from the bottle as the same is being filled.

In prior machines, the filling valve comprised a long tube which was received into the bottle, a valve being also provided to close the bottom end of the tube when the bottle was filled. As the bottle was lowered off the tube, the space occupied by the tube prevented the bottle from being filled up sufficiently. It is therefore an object of this invention to provide means to fill the bottle to make up for the displacement of the tube as the bottle is lowered after filling.

In prior machines of the character described, there was provided an elongated tube which passed downwardly into the bottle, and through the tube there extended an elongated, central, axial stem, carrying a pear shaped valve at its lower end, to close the lower end of the tube. With such construction, should the tube break it could not be easily taken off the pear valve. Furthermore, since the valve closed at the bottom of the tube, which is located at the bottom of the bottle, during the filling operation, considerable foam is caused within the bottle.

In accordance with the present invention, the tube projects into the bottle but the pear shaped valve is above the upper end of the tube and not within the bottle, thus causing less foaming because the valve is not shut within the bottle. Furthermore, with my improved construction, should the tube break it could easily be removed and replaced. Furthermore, the seat for the pear valve being remote from the lower end of the tube is well protected and cannot be damaged by glass should the bottle break.

In prior machines, since the pear valve was at the bottom end of the tube, the seat for the

pear valve has often been damaged and cut by glass upon a bottle breaking. With my improved construction, furthermore, the stem for the pear valve is considerably reduced in length, and is hence, more rigid and durable.

Yet another object of this invention is to provide in apparatus of the character described, a pressure relief valve to release the pressure of the air within the bottle during the filling operation, spring means being provided to retain the pear valve closed when the pressure relief valve is open, said spring means being adjustable to accommodate the pressure in the beverage supply tank.

Still another object of this invention is to provide a strong, rugged and durable machine of the character described, which shall be inexpensive to manufacture, smooth and positive in operation, and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is a side elevational view of part of a bottle filling machine provided with filling mechanism, embodying the invention;

Fig. 2 is an elevational view of the improved filling valve with parts broken away and in cross-section;

Fig. 3 is a side elevational view of the structure shown in Fig. 2; and

Fig. 4 is a cross-sectional view taken on line 4—4 of Fig. 1.

Referring now in detail to the drawings, 10 designates a bottle filling machine, embodying the invention. The same may comprise a usual circular tank 11 for carbonated beverage or beer under pressure. The tank 11 may be closed at the top by a cover 12. Air under pressure is fed to the tank 11 through a pipe 13, usually designated the counter pressure.

Extending into the tank 11 is my filling valve 15. The same comprises a member 16 projecting into an opening 17 in the bottom wall 18 of the tank 11. A rubber gasket 19 may be provided to seal the connection between the member 16 and the tank 11.

Member 16 comprises a top wall 20 formed with

a central through opening 21, and a downwardly skirted portion 22, forming a chamber 23 on the underside thereof. The top wall 20 is formed with a passage 24, communicating with chamber 5 23. Attached to the top wall 20 is a spring 10 pressed relief valve 25 adapted to open the passage 24 and chamber 23 to the atmosphere, when said valve is being pushed open in the manner hereinafter described. Said top wall 20 is furthermore formed with a radial nipple 26, and an L-shaped opening 27, connecting the nipple 15 with the top of said wall 20.

Member 16 is furthermore formed with a pair of upwardly extending parallel sockets 16a, projecting into the beverage tank 11, and with inclined passages 16b, connecting the socket 16a with the chamber 23.

Attached to the skirted portion 22 of member 16 by a coupling 29, is a tubular member 30 having an externally screw threaded portion 31 at its lower end. Screwed to said screw threaded portion 31 is a member 32, having a socket to receive said portion 31, and having a bottom wall 33 formed with a central through opening 34. 25 The upper surface of said bottom wall 33 forms a valve seat, for the purpose hereinafter appearing.

The under-surfaces of the bottom wall 33 may be countersunk to receive a rubber washer 36, 30 held on said member by a coupling 37. Member 32 is formed with a radial nipple 38 and with a passage 39 passing through the nipple and extending to the upper surface of the bottom wall 33.

35 Extending through the central opening 34 in member 32, is a tubular member 42, and fixed to the upper end of the tubular member 42 is a valve 43 adapted to be seated on the valve seat 33. A coil compression spring 44 is interposed 40 between the valve 43 and the underside of the top wall 20 of member 16, for normally retaining the valve 43 seated on its valve seat, to close the passage 39.

Mounted on the member 20 is a tubular member 45, extending through the opening 21 in the top wall 20. The member 45 is formed with a downwardly projecting internally screw threaded tubular portion 50. The top of member 45 is open, and is closed by a cap 51 having a central 50 beveled opening 52, forming a valve seat, as will appear hereinafter. The upper portion of tubular member 45 is connected to the L-shaped passage 27 by a tube 53.

Screwed to the screw threaded tubular portion 55 50 is an elongated tube 56, passing through the tubular member 42, and adapted to project into the bottle 57 to be filled. Screwed to the lower end of tube 56 is a cap 58 formed with a plurality of perforations 59, for the purpose hereinafter 60 appearing.

Slidably mounted on the tube 56 is a bell 60, having a downwardly and outwardly flaring portion 61 at its lower end, and a central opening 62, to receive the tube 56. At the upper end of 65 the flaring portion 61 is a rubber gasket 64, adapted to contact the top of the bottle. As the bell moves upwardly, it contacts the lower end of tube 42, to raise the valve 43 and uncover the passage 39, for the purpose hereinafter appearing.

Mounted in the sockets 16a and disposed within the beverage tank 11, are vertical tubular members 70 carrying a diaphragm housing 71 at its 75 upper end. The tubular members 70 are con-

nected by passages 72 to a chamber 73 above the diaphragm 74.

Attached to the housing 71 is a U-shaped member 75, extending below said housing and formed with a central opening 76. The bottom 5 wall 77 of the housing has a central opening 78, whereby the underside of the diaphragm 74 is open to the pressure within the tank 11. Attached to the center of the middle of the diaphragm, is a stem 79 passing through the opening 76 in the U-shaped strap 75.

Screwed to the bottom of the stem 79 is a rod 80, having a pear shaped valve 81 at its lower end, disposed within the tubular member 45 and adapted to be seated on the beveled valve seat 52 in the cap 51. The rod 80 is screw threaded at its upper end, and screwed thereon is a collar 84. Interposed between the collar 84 and the strap 75 is a coil compression spring 87, normally pressing the stem 79 downwardly. 20

The spring 87 normally does not exert sufficient force to keep the valve 81 open when the pressure above the diaphragm is reduced, that is, the pressure within the supply tank 11 is sufficient to raise the diaphragm against the 25 spring pressure 87, to close the pear shaped valve 81, when the pressure above the diaphragm in the chamber 73, and in the tubes 70 and chamber 23 is reduced.

Attached to the nipple 26 is a pipe 90 connected to a usual counter pressure air supply pipe 91. Interposed in the pipe 90 is a check valve 92, permitting the air to pass through the pipe 90 to the nipple 26. In pipe 90 there is also a band controlled valve 94. Connected to the nipple 38 is 35 a pipe 96, likewise connected to the pipe 91, to receive a supply of air under pressure.

It will be understood that the tank 11 is annular and rotates about the axis of the machine. The tank is provided with a number of filling 40 valves 55, and usual means is provided for moving the bottles 57 upwardly for the filling operation and for lowering the bottles after they have been filled.

Normally the pressure from pipe 13 entering 45 tank 11 which contains carbonated beverage lifts the diaphragm 74 upwardly to close the pear shaped valve 81 against the valve seat 52. When the bottle is down, the bell 60 is likewise down, and hangs on the member 53. When the bell is 50 down, the tube 42 is also down, and the spring 44 closes the valve 43. At the same time pressure coming through pipe 90 enters through passage 27 and is exhausted through the openings 59 at the bottom end of the tube. When the machine 55 is idle the valve 94 is closed.

When the machine operates, the bottles come up in rapid succession, and the periods when the air exhausts through the bottom end of the tube 56 are relatively short. When the bottle comes 60 up, the bell 60 is lifted, the tube 56 entering the bottle. The bell engages the bottom end of the tube 42 to lift the valve 43 against the pressure of spring 44. Air pressure from pipe 96 then enters passage 39 and chamber 23, passing 65 through passages 16b, upwardly through pipe 70 and passage 72 to the chamber 73, above the diaphragm 74. The pressure in chamber 73 causes the diaphragm to be pushed downwardly to open the valve 81 and permit carbonated beverage to 70 pass from tank 11, through valve opening 52 into tube 45, and through tube 56 and the openings 59, to spray against the inside of the bottle.

As the machine revolves, the spring pressed valve 25 strikes angular spaced abutments 100, to 75

open the pressure relief valve and permit the air within the bottle to pass upwardly between the tube 56 and the bell 60, and also between said tube 56 and the tube 42, upwardly through the chamber 23, passage 24, and out to the atmosphere.

It will be noted that the tube 56 is spaced and concentric with the tube 42 and the bell 60 to permit the air in the bottle to escape when the valve 25 is opened momentarily when the machine rotates. The periodic relief of the air permits the bottle to fill faster and reduces the resistance to filling, whereby less pressure is needed in the beverage supply tank 11.

15 The valve 25 is only opened for very short intervals. While it is open, the pressure in chamber 23, and hence, in passage 16b, tube 72 and chamber 73 is also reduced. However, the spring 87 keeps the pear valve open for the short 20 interval during which the valve 25 is open, until the pressure in the chamber 73 builds up again upon valve 25 closing. After the bottle is filled, it comes down, valve 43 closes to shut off the supply of air under pressure to the chamber 23.

25 It will be noted that the pear valve 81 is remote from the bottom end of the tube. Since the closing of the valve is not at the bottom of the tube, less agitation results when the valve is closed. Furthermore, the valve 81 and the valve 30 seat 52 are protected and cannot be damaged or cut by glass should a bottle break. If the tube 56 breaks, the remaining stem can be readily unscrewed and a new tube screwed into place.

When the bottle is lowered and valve 43 is 35 closed, the pressure in chamber 73 is reduced so that the pressure in the supply tank is sufficient to raise and close the pear valve 81. As the bottle lowers, the space which was occupied by the tube is filled by the beverage within the 40 tube 56 and within the tube 45. The pressure from pipe 99 causing the beverage within the tubes 56 and 45 to be forced downwardly into the bottle to fill the bottle.

45 In prior apparatus, where the valve was at the bottom of the tube, lifting of the tube prevented the bottle from being completely filled. In prior constructions, furthermore, the stem or rod for the pear valve 81 passed entirely through the tube 56. With the present construction, the 50 length of the stem for the pear valve is considerably reduced.

55 It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter 60 herein set forth or shown in the accompanying drawings is to be interpreted as illustrative and not in a limiting sense.

Having thus described my invention, I claim as new and desire to secure by Letters Patent:

55 1. In bottle filling machinery of the character described, a beverage tank, means for supplying air under pressure to said tank, said tank having a valve opening adjacent the bottom thereof, an elongated tube mounted on said tank and extending downwardly therefrom, the upper end of said tube communicating with the valve opening, said tube being adapted to be received in a bottle, a valve for closing said opening, means controlled by pressure in said tank for closing 70 said valve and for opening said valve to permit

beverage in said tank to pass down through said valve opening into said tube for filling the bottle, and conduit means for connecting the upper end of said tube, just below said valve opening, with a source of air pressure to force beverage in said tube down into the bottle, upon closing the valve.

2. In a bottle filling machine, a supply tank for carbonated beverage, a tubular member on said supply tank and extending downwardly therefrom, and adapted to be received in a bottle as 10 the bottle is lifted upwardly, said tank having a valve opening communicating with said tube, and disposed at the upper end of the tube, valve means adapted to close said valve opening, means controlled by pressure in said tank for closing 15 said valve means and for opening said valve means against the pressure within the supply tank, to permit carbonated beverage from the supply tank to pass through the valve opening and into the bottle, and conduit means to connect 20 the upper end of the tube, below said valve opening, with a pressure supply for forcing beverage within the tube, after the valve means is closed, down into the bottle as the bottle is lowered.

3. In a bottle filling machine, a supply tank for carbonated beverage, a tubular member on said supply tank and extending downwardly therefrom, and adapted to be received in a bottle as 25 the bottle is lifted upwardly, said tank having a valve opening communicating with said tube, and disposed at the upper end of the tube, valve means adapted to close said valve opening, means controlled by pressure in said tank for closing said valve means and for opening said valve means against the pressure within the supply tank, to 30 permit carbonated beverage from the supply tank to pass through the valve opening and into the bottle, means whereby pressure may be applied for forcing beverage within the tube, after the valve means is closed, down into the bottle as 40 the bottle is lowered, and means for periodically releasing air from the bottle during the filling operation.

4. In a bottle filling machine, a supply tank for carbonated beverage under pressure, said tank 45 having a valve opening at the bottom thereof, a tube extending downwardly from the tank and communicating with said valve opening, a housing surrounding the upper end of the tube forming a chamber and provided with a bottom wall 50 having an opening through which said tube passes, and with an inlet passage communicating with said chamber, means for supplying air under pressure to said passage, a chamber within said supply tank closed by a diaphragm, conduit 55 means interconnecting the first chamber with the second chamber, a rod fixed to said diaphragm and provided with a valve at its lower end adapted to close said valve opening, when the pressure in the supply tank is greater than 60 the pressure within said chambers, a second valve within said first chamber adapted to close said inlet passage, spring means for normally pressing said second valve downwardly for retaining said second valve in position for closing said passage, a sleeve surrounding said tube and fixed at its upper end to said valve and passing through the opening in the bottom wall of said housing and adapted to be lifted by a bottle as the latter 65 is moved upwardly to filling position, to uncover said passage, to permit air under pressure to pass to the first chamber and through said conduit to said second chamber to open said first valve and permit beverage to pass down through the tube into the bottle, and means for supplying 70

75 said valve and for opening said valve to permit

air under pressure to the upper end of said tube.

5. In a bottle filling machine, a supply tank for carbonated beverage under pressure, said tank having a valve opening at the bottom thereof, a tube extending downwardly from the tank, the upper end of said tube communicating with said valve opening, a housing surrounding the upper end of the tube forming a chamber and provided with a bottom wall having an opening through which said tube passes, and with an inlet passage communicating with said chamber, means for supplying air under pressure to said passage, a chamber within said supply tank closed by a diaphragm, conduit means interconnecting the first chamber with the second chamber, a rod fixed to said diaphragm and provided with a valve at its lower end adapted to close said valve opening, when the pressure in the supply tank is greater than the pressure within said chambers, a second valve within said first chamber adapted to close said inlet passage, spring means for normally pressing said second valve downwardly for retaining said second valve in position for closing said passage, a sleeve surrounding said tube and fixed at its upper end to said valve and passing through the opening in the bottom wall of said housing and adapted to be lifted by a bottle as the latter is moved upwardly to filling position, to uncover said passage, to permit air under pressure to pass to the first chamber and through said conduit to said second chamber to open said first valve and permit beverage to pass down through the tube into the bottle, means for supplying air under pressure to the upper end of said tube, said sleeve being spaced from said tube, to permit air in the bottle to pass up to the first chamber, a spring pressed relief valve on said first chamber, and means for periodically opening said last valve during the filling operation to release the air from the bottle as it is being filled.

6. In a bottle filling machine, a supply tank for carbonated beverage under pressure, said tank having a valve opening at the bottom thereof, a tube extending downwardly from the tank and communicating with said valve opening, a housing surrounding the upper end of the tube forming a chamber and provided with a bottom wall having an opening through which said tube passes, and with an inlet passage communicating with said chamber, means for supplying air under pressure to said passage, a chamber within said supply tank closed by a diaphragm, conduit means interconnecting the first chamber with the second chamber, a rod fixed to said diaphragm and provided with a valve at its lower end adapted to

close said valve opening, when the pressure in the supply tank is greater than the pressure within said chambers, a second valve within said first chamber adapted to close said inlet passage, spring means for normally pressing said second valve downwardly for retaining said second valve in position for closing said passage, a sleeve surrounding said tube and fixed at its upper end to said valve and passing through the opening in the bottom wall of said housing and adapted to be lifted by a bottle as the latter is moved upwardly to filling position, to uncover said passage, to permit air under pressure to pass to the first chamber and through said conduit to said second chamber to open said first valve and permit beverage to pass down through the tube into the bottle, said sleeve being spaced from said tube, to permit air in the bottle to pass up to the first chamber, a spring pressed relief valve on said first chamber, means for periodically opening said last valve during the filling operation to release the air from the bottle as it is being filled, spring means for urging said rod in a direction for opening the valve thereon, and means to adjust said spring means.

7. In bottle filling machinery of the character described, a beverage tank, said tank having a valve opening adjacent the bottom thereof, an elongated tube attached to said tank and extending downwardly therefrom, the upper end of said tube communicating with said valve opening, said tube being adapted to be received in a bottle to be filled, a chamber closed by a diaphragm separating said chamber from said tank, a valve for closing said valve opening attached to said diaphragm, said diaphragm being controlled by pressure in said tank to close said valve, and by pressure in said chamber for opening said valve to permit beverage in said tank to pass down through said valve opening into said tube for filling said bottle, a housing surrounding the upper end of the tube, forming a chamber provided with a bottom wall, having an opening through which the tube passes, said second chamber having an inlet passage, a valve for closing said inlet passage, a conduit interconnecting the second chamber with the first chamber, a bell slidably mounted on said tube and adapted to be lifted by a bottle to be filled, said bell having means to open the valve which closes the inlet passage to the second chamber, said second chamber being provided with a spring pressed normally closed valve, and means for periodically opening said valve.

GEORGE J. VALAVAN. 55
